(57) CLAIM

The ornamental design for a finger stylus, as shown and described.

DESCRIPTION

FIG. 1 is an isometric view of a finger stylus;
 FIG. 2 is a front view thereof;
 FIG. 3 is a rear view thereof;
 FIG. 4 is a left hand side view thereof, wherein a right-hand side view is a mirror image of the left-hand side view;
 FIG. 5 is a top view thereof;
 FIG. 6 is a bottom view thereof; and,
 FIG. 7 is another isometric view thereof with a human hand in the environment for illustration.
